UNITED STATES PATENT OFFICE

VERA V. MARCUS, OF LOS ANGELES, CALIFORNIA

DESIGN FOR A BOOTH

Application filed October 2, 1929. Serial No. 32,914. Term of patent 14 years.

To all whom it may concern:

Be it known that I, VERA V. MARCUS, a citizen of the United States, and a resident of Los Angeles, Los Angeles County, California, have invented a new, original, and ornamental Design for a Booth, of which the following is a specification, reference being had to the accompanying drawings, forming part thereof.

The figure is a front perspective view of a booth showing my new design. The opposite side of the design is similar.

I claim:

The ornamental design for a booth, as shown and described.

VERA V. MARCUS.
